[57] CLAIM

The ornamental design for the one-piece closure with anti-finger intrusion lift-tab, as shown and described.

DESCRIPTION

FIG. 1 is a perspective view of a one-piece closure with anti-finger intrusion lift-tab showing our new design in the open position, the package to which the closure is attached being shown in phantom lines to depict the environment in which the lift-tab is used, and forming no part of the design hereof;

FIG. 2 is an enlarged view thereof;

FIG. 3 an enlarged back view thereof;

FIG. 4 is an enlarged side view thereof, the opposite side being identical;

FIG. 5 is an enlarged top view thereof;

FIG. 6 is an enlarged bottom view thereof;

FIG. 7 is a perspective view of a one-piece closure with anti-finger intrusion lift-tab showing our new design in the closed position, the package to which the closure is attached being shown in phantom lines to depict the environment in which the lift-tab is used, and forming no part of the design hereof;

FIG. 8 is an enlarged front view thereof;

FIG. 9 is an enlarged back view thereof;

FIG. 10 is an enlarged side view thereof, the opposite side being identical;

FIG. 11 is an enlarged top view thereof; and,

FIG. 12 is an enlarged bottom view thereof.
